REFRIGERATOR HAVING A DOOR WITH A
COOLING UNIT MOUNTED THEREIN

John R. Prosek, Riverside, Ill., assignor to International Harvester Company, a corporation of New Jersey

Application June 20, 1947, Serial No. 755,904

10 Claims. (Cl. 62—116)

1

This invention relates to a refrigerator and more particularly to a closure element for the access opening in a refrigerator cabinet having a food-storage compartment.

Refrigerators of the household type generally assume two forms: one, the upright-type which has its food-storage compartment opening at its front and closed by a hinged door; the other, a chest-type provided with a hinged cover at its top, usually used in the storage of food and similar articles at sub-freezing temperatures. In both boxes it has been heretofore common practice to provide a separate compartment for the refrigerant-circulating machinery and to utilize the door or cover merely as a closure member. At the same time conventional design involved construction in which the refrigerating apparatus, including the evaporator, condenser and compressor, is readily removable as a unit.

According to the present invention the foregoing elements of construction are embodied in a closure member that serves the dual function of closing the food-storage compartment and of carrying the refrigerating apparatus as a removable unit. With a construction of the type disclosed herein the cover or door, together with the refrigeration apparatus, may be removed for repair or adjustment and may be replaced by another similar unit or element while such repair or adjustment is being accomplished. It is therefore the principal object of the invention to provide an improved refrigerator including a closure member of the type embodying the advantages just described. It is a further object of the invention to provide a refrigeration unit embodied as the closure member of a simple and inexpensive cabinet or box, whereby the cabinet may be inexpensively constructed and fitted with the removable closure. Other objects of the invention are: to provide a closure comprising inner outer sheets secured together at their marginal edges to provide a housing space for containing refrigeration apparatus; to provide for the mounting of an evaporator in proximity to the inner sheet and a condenser in proximity to the outer sheet, both the condenser and evaporator preferably being contained within the housing space between the sheets; to connect the evaporator and condenser in heat-transfer relationship with the inner and outer sheets respectively; to provide the evaporator and condenser relatively coextensive in area with the inner and outer sheets respectively; to provide an intermediate sheet between the inner and outer sheets on which a refrigerant compressor may be mounted; and to

2

provide the closure of louvered construction whereby to facilitate the circulation of air over the condenser and compressor.

The foregoing and other objects and desirable features of the invention will appear as a disclosure of a preferred embodiment is more fully made in the following detailed description and accompanying sheet of drawings, in which the single figure represents a transverse sectional view through a refrigerator equipped with a closure element constructed according to the principles of the present invention.

For the purposes of clarity and brevity in the following description, reference will be made to upper and lower and interior and exterior parts. These expressions, like others to be used, refer to only one of many forms that the invention may assume; hence, the disclosure should be taken as illustrative and not limiting.

20 The refrigerator chosen for the purposes of illustration is of the so-called freezer-chest type used for the storage of food and other articles at subfreezing temperatures. This refrigerator includes a cabinet or chest having walls defining a 25 food storage compartment 10 which is provided with an opening 11 through which access may be had to the food-storage compartment. The food-storage compartment is delineated by an inner shell or tank 12 associated in spaced relation to 30 and insulated from an outer tank or shell 13. The tanks are preferably formed of sheet metal construction and each has an upper inwardly turned flange cross-connected by a breaker strip 14 of insulating material. The construction just 35 described is generally conventional and may embody other details of construction not important to the present invention.

The cabinet is preferably square or rectangular in cross-section, although it may be circular, and 40 the breaker strip 14 is preferably continuous about the access opening 11. The breaker strip serves to support thereon a superimposed cover or closure element generally indicated by the numeral 15. This element includes an intermediate 45 sheet 16, an inner sheet or liner 17, and an outer sheet or liner 18. The intermediate sheet 16 is relatively larger in area than the opening 11, so that marginal edge portions thereof may extend laterally of or overlie a peripheral gasket 19 superimposed on the breaker strip 14. The outer sheet or liner 18 is preferably domed at its center and is preferably provided with an integral peripheral wall 20, the lower portions of which terminate in an integral turned flange 21. The flange 21 lies substantially in the same plane as

the intermediate sheet 16 and is spaced peripherally therefrom. The space between the flange 21 on the outer sheet 18 and the marginal edge portions of the intermediate sheet 16 is closed by a breaker strip 22. The intermediate sheet 16 may be rigidly supported by or connected to the outer sheet 18 by means of a plurality of corner brackets 23 (only one of which is shown). This bracket is shown as being rigidly secured to the outer sheet 18 as by spot welding, and the bracket is further rigidly connected to the intermediate sheet 16 by securing means including insulating material 24.

The relationship between the intermediate sheet 16, domed outer sheet 18, and peripheral outer wall 20 is such as to provide a housing space 25 within the sheets. This housing space serves to accommodate refrigerant circulating apparatus including a motor-compressor unit 26 seated on and carried by a depressed intermediate portion 27 of the intermediate sheet 16. The interior surface of the outer sheet 18 carries a condenser 28. The condenser is preferably of coil construction and is spread out over the interior surface of the outer sheet so as to be substantially coextensive in area therewith. The outer sheet 18 is preferably of sheet metal or other heat-conducting material, and the condenser is secured thereto in heat-transfer relationship to secure to greatest advantage the heat-dissipating qualities of the outer sheet. The means for connecting the condenser to the interior surface of the outer sheet may take the form of a plurality of strips 29 including a plurality of integral U-shaped portions embracing the coils of the condenser and secured to the outer sheet, as by spot welding, between the coils.

The inner sheet 17 is substantially smaller in area than the intermediate sheet 16 so as to fit within the access opening 11 of the food storage compartment 10. The inner sheet has its marginal edges provided with upwardly extending integral flange portions 30 which terminate in laterally extending flanges 31 rigidly secured to the intermediate sheet 16. The securing means is preferably removable and may include insulating material to insulate the sheet 17 from the sheet 16. The sheets 16 and 17 are spaced apart and carry therebetween an evaporator in the form of a continuous coil 32. This coil is substantially coextensive in area with the interior surface of the sheet 17 and is secured to the sheet 17 in heat-transfer relationship thereto, the sheet 17 being of sheet metal or other heat-conducting material. The means for accomplishing the securing of the evaporator coil 32 to the sheet 17 may include a plurality of strips like the strip 33, having integral inverted U-shaped portions embracing the coils and spot welded between the coils to the sheet 17. This arrangement utilizes to greatest advantage the entire surface of the sheet 17 as part of the evaporator.

The refrigerant circulating system or apparatus includes the compressor 26, condenser 28 and evaporator coil 32, and further includes a low-pressure line 34 between the evaporator and compressor, a refrigerant line 35 between the compressor and condenser, and a high-pressure line 36 including a capillary tube 37 between the condenser and evaporator. Insulating material 38 is provided in the space between the evaporator coil 32 and the proximate surface of the intermediate sheet 16. The apparatus may further include a cold control 39 of conventional construction responsive to a cold control bulb 40 carried by the

exterior surface of the inner sheet 17 so as to be within the food compartment 10. This construction may be conventional and forms no part of the present invention.

The peripheral wall portion 20 of the outer sheet 18 is louvered at 41 and the central upper portion of the outer sheet 18 is provided with an opening 42 closed by a louvered cover 43. As shown by the arrows, cooling air may circulate through the louvers 41 and the louvers in the cover 43 over the condenser coils 28 and further over the motor-compressor 26 and refrigerant lines within the housing space 25. The cover 43 may be made removable to facilitate access to the compartment 25.

The cover or closure element 15 may be hinged or otherwise secured to the chest or cabinet so that it may be opened or closed to provide access through the opening 11 to the food storage compartment 10 and is further constructed so as to be completely removable therefrom in the event of failure of the refrigerating apparatus to function, in which case the closure element may be replaced by a like element without causing any cessation of refrigeration. In the meantime the removed unit may be taken to any convenient service location for repair or adjustment.

The several advantages and features of the invention have been pointed out heretofore. Other advantages and features will undoubtedly occur to those skilled in the art, as will numerous modifications and alterations in the preferred construction illustrated. It will be understood, of course, that these deviations may be accomplished without sacrificing any of the principles of the invention and without departing from the spirit and scope of the appended claims.

What is claimed is:

1. In a refrigerator including a cabinet forming a food-storage compartment having an access opening, a closure element for the opening, comprising: an inner and an outer liner spaced apart to include a housing space therebetween; means securing the liners together at their marginal edge portions; and refrigerant circulating apparatus housed in the space between the liners and including an evaporator in proximity to and substantially coextensive in area with the inner liner, a condenser in proximity to and substantially coextensive in area with the outer liner, and refrigerant circulating connections between the evaporator and condenser.
2. In a refrigerator including a cabinet forming a food-storage compartment having an access opening, a closure element for the opening, comprising: an inner and an outer liner, both of sheet metal, spaced apart to include a housing space therebetween; means securing the liners together at their marginal edge portions; an evaporator within the housing space and carried by and spread out over the surface of the inner liner and including a heat-transfer connection to said inner liner; a condenser within the housing space and carried by and spread out over the surface of the outer liner and including a heat-transfer connection to said outer liner; means insulating the inner liner from the outer liner; and a refrigerant compressor within the housing space between the liners including refrigerant-circulating connections between the evaporator and compressor, the compressor and condenser, and the condenser and evaporator.
3. In a refrigerator having a cabinet including walls forming a food-storage compartment provided with an access opening, a closure element

for said opening, comprising: a first sheet of sufficient area to cover said opening and to engage the cabinet walls around the opening; a second sheet of heat-conducting material generally parallel and spaced inwardly from the first sheet and reduced in area to fit within said opening; means securing the second sheet to the first sheet; an evaporator positioned between the sheets and secured in heat-transfer relationship to the inner sheet and being spread out substantially over the area of said inner sheet; insulating material between the evaporator and first sheet; a generally dome-shaped third sheet spaced outwardly from the first sheet and including peripheral wall portions secured to the first sheet to provide a housing space between the first and third sheets; a condenser in said housing space and spread out substantially over and in heat-transfer relationship with the interior surface of the third sheet; means providing louvers in the peripheral wall portions and in the domed portion of said third sheet for the circulation of air over the condenser; and a refrigerant circulating circuit including the aforesaid condenser and evaporator and further including a compressor carried by the first sheet in the housing space between the first and third sheets.

4. In a refrigerator having a cabinet including walls forming a food-storage compartment provided with an access opening, a closure element for said opening, comprising: a first sheet of sufficient area to close said opening; a second sheet of heat-conducting material generally parallel and spaced inwardly from the first sheet; means securing the second sheet to the first sheet; an evaporator positioned between the sheets and secured in heat-transfer relationship to the inner sheet and being spread out substantially over the area of said inner sheet; a third sheet spaced outwardly from the first sheet and including peripheral wall portions secured to the first sheet to provide a housing space between the first and third sheets; a condenser in said housing space and spread out substantially over and in heat-transfer relationship with the interior surface of the third sheet; means providing louvers in the peripheral wall portions of said third sheet for the circulation of air over the condenser; and a refrigerant circulating circuit including the aforesaid condenser and evaporator and further including a compressor carried by the first sheet in the housing space between the first and third sheets.

5. In a refrigerator having a cabinet including walls forming a food-storage compartment provided with an access opening, a closure element for said opening, comprising: a first sheet of sufficient area to close said opening; a second sheet of heat-conducting material generally parallel and spaced inwardly from the first sheet; means securing the second sheet to the first sheet; an evaporator positioned between the sheets in proximity to the inner sheet and being spread out substantially over the area of said inner sheet; a third sheet spaced outwardly from the first sheet and including peripheral wall portions secured to the first sheet to provide a housing space between the first and third sheets; a condenser in said housing space and spread out substantially over and in proximity to the interior surface of the third sheet; means providing louvers in the peripheral wall portions of said third sheet for the circulation of air over the condenser; and a refrigerant circulating circuit including the aforesaid condenser and evapo-

rator and further including a compressor carried by the first sheet in the housing space between the first and third sheets.

6. In a refrigerator having a cabinet including walls forming a food-storage compartment provided with an access opening, a closure element for said opening, comprising: a first sheet of sufficient area to close said opening; a second sheet of heat-conducting material generally parallel and spaced inwardly from the first sheet; means securing the second sheet to the first sheet; an evaporator positioned between the sheets and secured in heat-transfer relationship to the inner sheet; a third sheet spaced outwardly from the first sheet and including peripheral wall portions secured to the first sheet to provide a housing space between the first and third sheets; a condenser in said housing space in heat-transfer relationship with the interior of the third sheet; means providing louvers in the peripheral wall portions of said third sheet for the circulation of air over the condenser; and a refrigerant circulating circuit including the aforesaid condenser and evaporator and further including a compressor carried by the first sheet in the housing space between the first and third sheets.

7. In a refrigerator having a cabinet including walls forming a food-storage compartment provided with an access opening, a closure element for said opening, comprising: a first sheet of sufficient area to close said opening; a second sheet of heat-conducting material generally parallel and spaced inwardly from the first sheet; means securing the second sheet to the first sheet; an evaporator positioned between the sheets and secured in heat-transfer relationship to the inner sheet; a third sheet spaced outwardly from the first sheet and including peripheral wall portions secured to the first sheet to provide a housing space between the first and third sheets; a condenser in said housing space in heat-transfer relationship with the interior surface of the third sheet; and a refrigerant circulating circuit including the aforesaid condenser and evaporator and further including a compressor carried by the first sheet in the housing space between the first and third sheets.

8. In a refrigerator including a cabinet forming a food-storage compartment having an access opening, a closure element for the opening, comprising: an inner and an outer liner spaced apart to include a housing space therebetween, and having said outer liner of generally dome-shape to increase the capacity of said space for the purpose of containing refrigeration apparatus; means securing the liners together at their marginal edge portions; and refrigerant circulating apparatus housed in the space between the liners and including an evaporator in proximity to the inner liner, a condenser in proximity to the outer liner and refrigerant circulating connections between the evaporator and condenser.

9. In a refrigerator including a cabinet forming a food-storage compartment having an access opening, a closure element for the opening, comprising: an inner and an outer liner spaced apart to include a housing space therebetween; means securing the liners together at their marginal edge portions; said marginal edge portions securing means including peripheral wall portions; refrigerant circulating apparatus housed in the space between the liners and including an evaporator in proximity to the inner liner, a condenser in proximity to the outer liner, and refrigerant

circulating connections between the evaporator and condenser; and louver means in said peripheral wall portions arranged to direct air over said condenser.

10. The invention set forth in claim 9, in which: 5 additional louvers are provided in the outer liner and arranged to cooperate with the peripheral wall louvers for the circulation of air over the condenser.
